L. J. WAHL

CLIPPER

Filed May 1, 1924

Fig. 4

Inventor
Leo J. Wahl.

by May H. Zabel Atty.

UNITED STATES PATENT OFFICE.

LEO J. WAHL, OF STERLING, ILLINOIS.

CLIPPER.

Application filed May 1, 1924. Serial No. 710,312.

To all whom it may concern:

Be it known that I, LEO J. WAHL, a citizen of the United States, residing at Sterling, in the county of Whiteside and State of Illinois, have invented a certain new and useful Improvement in Clippers, of which the following is a full, clear, concise, and exact description, reference being had to the accompanying drawings, forming a part of this specification.

My invention relates to hair clippers and more particularly to vibratory clippers operated by an electromagnet to which alternating current is supplied.

It is a purpose of my invention to provide a clipper construction whereby the disadvantages existing in clippers of the prior art are overcome. It has been customary in the past to extend the vibratory member comprising the armature rearwardly at one side of the case or casing of the clipper and to so mount the same that the vibratory movement thereof takes place about a center near the one side of the casing. The mounting is preferably made by means of a resilient member such as a blade spring, although any other suitable means for obtaining a vibratory action can be used. When the vibratory means carrying the blade is mounted in this manner, the tendency will be for the blade to move back from the cutting edge more at one end of its movement than at the other end. This is due to the fact that the blade travels in the arc of a circle whose center is the point of securement or mounting of the vibratory member on the casing. It is a purpose of my invention to overcome this condition and to obtain substantially the same receding of the teeth of the movable blade relative to the teeth of the stationary blade on both ends of its movement, thus considerably reducing the amount which the blade recedes as a maximum and providing a device that has a much better cutting action. This result is obtained by mounting the resilient member forming a part of the vibratory mechanism either on or near the center line of the device.

In order to obtain this result, it is necessary to provide an inwardly extending or offset portion on the vibratory member to thus bring the end thereof, that is mounted on the casing inwardly from the side of the casing. The portion of the vibratory member that forms the armature must be located

near the side of the casing because the electro-magnet extends transversely of the casing and as it is desirable to make the devices of this character as small in width as possible so that the same will fit the hand readily, the electro-magnet occupies substantially the entire width of the casing except the space that is necessary for the vibratory movement of the vibratory member between the electro-magnet and the wall of the casing.

The result desired may be obtained in various ways, as for example by offsetting either the armature or the resilient member forming part of the vibratory member so that the same will lie at or near the center line of the device, or by gradually inclining the vibratory member inwardly so that the secured end thereof would lie near the center line of the blades when in central position.

Other objects and advantages of my invention will appear as the description of the accompanying drawings, proceeds. However, I desire to have it distinctly understood that I do not intend to limit myself to the exact details shown or described, but that I intend to include as part of my invention all such obvious changes and modifications of parts as would occur to a person skilled in this art and as would fall within the scope of the claims.

In the accompanying drawing:

Fig. 1 is a plan view of a clipper embodying my invention, the cover of the casing being removed;

Fig. 2 is a view partly in section and partly in side elevation of the device shown in Fig. 1 with the cover in place;

Fig. 3 is a fragmentary detail view of a different form of construction of a portion of the vibrating mechanism from that shown in Fig. 1; and

Fig. 4 is a fragmentary plan view of a slightly different construction.

The same numerals of reference are used to indicate identical parts in the various figures.

In the construction shown in Figs. 1 and 2, I provide a suitable case 4 having a cover 5 attached to the case as by means of a screw 6 which passes through the cover and into the pedestal 7, and I mount within the casing so formed a coil 8 having a core 9, which is held in place in the case as by screws 10, the coil 8 being provided with suitable leads 11.

for the supplying of the operating current which is preferably that known as an alternating current.

The stationary clipper blade 30 is mounted at one end of the case and preferably at an angle as shown in Fig. 2 and the movable clipper blade 11 is mounted above the stationary clipper blade and slides thereon, both of these blades being preferably serrated as shown at 12.

At the rear of the case 4, or opposite that end which carries the stationary clipper blade 30, a mounting 14 is provided for a blade spring 15, the connection being by means of a screw 16. The blade spring 15 carries an armature 17 which is of the shape shown in Fig. 1 and extends forwardly and is bent transversely to carry the guard 18 and bracket 19, the parts being connected together as by screws 20. The bracket 19 carries a driving and adjusting screw 21 to move the blade 11 and to hold it to its seat, while the guard 18, by its contact with the rib 22 of the blade 11, prevents this blade from turning on the lower end of 21 as on a pivot.

It is to be noted that the mounting 14 for the spring 15 brings the center of movement of the movable blade 11 practically into the center of the length of the blade so that the movement of this blade is harmonious on either side of its central point.

To adjust the tension of the spring 15, I provide a screw 23 which passes through the side wall of the case and is threaded through a pedestal 24, the end of the screw coming in contact with the spring 15.

In the construction shown in Fig. 3 the spring 15 is replaced by spring 25 and the armature 17 is replaced by the armature 26 which brings the joint between these two parts some distance further from the mounting 14 than in the construction shown in Fig. 1 though without materially modifying the action of the parts even though increasing the length of elasticity of the spring. It is, of course, to be understood that the members 25 and 26 bear substantially the same relation to the blades 11 and 30 as the members 15 and 17 as shown in Fig. 1.

In Fig. 4 is shown a slightly different construction of the vibratory member, in said figure the casing 4 has the electro-magnet comprising the coil 8 and armature 9 mounted therein by means of the screws 10, these parts being the same as shown in Fig. 1. The clipper blade construction and mounting at the forward end of the device is preferably the same as in Fig. 1 and is not shown in detail. The vibratory member comprising the resilient member 15' and the armature 17' corresponding to the members 15 and 17 in Fig. 1 is provided with a transversely extending portion 27 upon which the movable clipper blade is mounted in a

similar manner to that shown in Fig. 1 and 2. The resilient member 15' is secured to the lug or abutment 14' by means of the securing member 16 which is the same as that shown in Fig. 1. The vibratory member is adjusted in a similar manner to that in which the vibratory member in Fig. 1 is adjusted by means of the screw 23 passing through the pedestal 24 and having screw threaded engagement therewith.

It will be noted upon reference to Fig. 4 that the members 15' and 17' overlap and are secured together by means of suitable securing devices 29. It will be further noted that the member 15' and the member 17' are substantially straight and lie substantially in parallel planes instead of being offset as are the members 15 and 25 in Figs. 1 and 3. However, the angularity of the member 17' relative to the center line 28 of the device is such that the end 31 thereof, which is secured to the casing by the member 16 lies much nearer the center line of the device than the portion thereof lying between the electro-magnet coil 8 and casing sidewall 30 opposite thereto. It will be noted further that the secured end of said vibratory member is located near the center line of the device although the end thereof adjacent the transversely extending portion 27 is as near the sidewall of the casing as the same can be placed to permit the necessary vibration of the vibratory member.

Having thus fully described my invention, I claim:

1. In a clipper the combination of a case, a stationary clipper blade carried thereby, a movable clipper blade cooperating with the stationary blade, an alternating current electro-magnet in the case, an armature for the electro-magnet and located near one side of the case and for moving the movable clipper blade, driving and pressure connections between the armature and the movable clipper blade, and a mounting for the armature located on a line near the center of the clipper blade.

2. In a clipper the combination of a case, a stationary blade carried thereby, a movable blade cooperating with the stationary blade, an alternating current electro-magnet in the case and near that end thereof which carries the blades, an armature arranged near one side of the case and connected to move the movable blade, and a spring for carrying the armature and mounted in the case near the end opposite to that which carries the blades, said spring being mounted near the center of the case.

3. In a clipper the combination of a case, a stationary blade carried thereby, a movable blade cooperating with the stationary blade, an alternating current electro-magnet in the case and near that end thereof which carries the blades, an armature arranged near

one side of the case and connected to move the movable blade, and a spring for carrying the armature and mounted in the case near the end opposite to that which carries the 5 blades, said spring being mounted near the center of the case, and means for adjusting the tension of the spring.

4. In a device of the character described, a casing, an electro-magnet extending transversely of said casing from near one side thereof to near the other side thereof and a vibratory member in said casing having a blade mounted on one end thereof and mounted on said casing near the other end thereof, 10 said member lying between the end of said magnet and one side of said casing and having a portion lying nearer the center line of said casing rearwardly of said magnet.
- 15 5. In a device of the character described, a casing, an electro-magnet extending transversely of said casing from near one side thereof to near the other side thereof, and a vibratory member in said casing comprising an armature and a resilient mounting member connected therewith, having a blade mounted on one end thereof and mounted 20 on said casing near the other end thereof, lying between the end of said magnet and one side of said casing, and having portions extending toward the center line of said casing on both sides of said magnet. 45

In witness whereof, I hereunto subscribe my name this 25th day of April, A. D. 1924.

LEO J. WAHL.
